CLAIM

The ornamental design for a filter cartridge, as shown and described.

DESCRIPTION

FIG. 1 is an upper perspective view of a filter cartridge showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a lower perspective view of FIG. 1.

The broken lines in the drawings depict portions of the filter cartridge that form no part of the claimed design.

1 Claim, 7 Drawing Sheets(56)
